UNITED STATES PATENT OFFICE.

WILLIAM J. TUCKER, OF WASHINGTON, DISTRICT OF COLUMBIA.

ARMOR-PIERCING PROJECTILE.

1,408,148.

Specification of Letters Patent. Patented Feb. 28, 1922.

Application filed July 18, 1921. Serial No. 485,582.

To all whom it may concern:

Be it known that I, WILLIAM J. TUCKER, a citizen of the United States, and a resident of the city of Washington, in the District of Columbia, have invented certain new and useful Improvements in Armor-Piercing Projectiles, of which the following is a specification.

My invention relates to armor piercing projectiles and more particularly to the construction of the base thereof.

It has been customary in ballistic tests to have the projectile strike the armor plate at an angle of 90° or as near thereto as possible and if no internal weakness developed, the shell would punch its way through the resistant plate and explode beyond the target.

Recent requirements have, however, made it necessary in ballistic tests to change the angle of impact to an angle which is from 20 to 25° removed from the 90° angle heretofore used or, in other words, at an angle measuring from 70 to 65° to the armor plate. Considerable difficulty has been encountered in successfully putting shells through the test when fired at such an angle because the rear edge of the shell comes in contact with the hole torn by its point thereby fracturing the body of the shell and impairing its efficiency as a bursting charge-carrying medium, because the fracture to the shell body exposes the charge-carrying cavity.

The detrimental effect to shells as mentioned hereinbefore is occasioned by the change of axis of the shell as it pushes its way through the armor plate. As the shell strikes the armor plate at an angle its point will enter the armor punching a hole through the same. As the body of the projectile moves through the hole thus torn the axis of the shell which primarily was disposed at an angle with respect to the armor plate, tends to assume an angle of 90° with respect to the armor plate. This change of the axis of the shell will throw the rear edge of the shell heavily against the opposite side of the hole in the armor plate whereby the fracture of the shell hereinbefore mentioned results.

It is the object therefor of my invention to provide means whereby the shell will discard its rear edge upon penetration of the armor plate in order to avoid the same contacting or binding as it passes therethrough.

In carrying out my invention the base of the shell is provided with a circular groove, which groove extends to a point adjacent the

rear edge of the bandscore. This groove is in the nature of a weakening groove thereby providing a circular pre-determined point 60 of fracture for the rear edge of the shell. This pre-determined point of fracture is sufficiently to the rear of the explosive charge cavity to eliminate the possibility of the shell fracturing so as to expose this 65 cavity. Hence when the rear edge of the shell contacts with the hole in the armor plate, the rear edge will be broken off at the point outlined by the disposition of this weakening groove, thereby permitting the 70 rear end of the shell to pass through the hole without binding and allowing the charge-carrying cavity to remain intact.

The contact of the rear end of the shell with the hole in the armor plate, as just described, exerts a radial pressure upon the rear end of the shell. This sometimes causes a distortion of the rear edge of the shell which permits the base plug to fall out. By providing the circular groove in the base of 80 the shell the force of the contact of the rear edge of the shell with the opening in the armor plate will not be exerted upon the portion of the shell body immediately surrounding the base plug. This circular 85 groove will permit the outer section of the shell formed by this groove to give first, before any pressure is exerted upon the rest of the shell body.

It is essential that the mouth of this circular groove be closed to prevent the gases of the firing charge from entering therein, inasmuch as these gases might cause a premature fracture to the base of the projectile. In order, therefore, to close the mouth 95 of this circular groove, I provide a ring which forms a continuation of the flange of the base plug. The abutting faces of the base plug flange and of this ring are inclined so that a contact of the rear edge of 100 the shell will cause the ring to shear off the screws which fasten it to the base plug flange, thereby causing the ring to be dislodged and permitting a free movement of 105 the rear edge of the shell, assuring its fracture at the pre-determined point of weakness.

The various features of my invention will be made more apparent in the accompanying specification and drawings in which:

Fig. 1 shows the base of a projectile constructed in accordance with my invention,

Fig. 2 is a fragmentary elevation, partly in section of the structure shown in Fig. 1,

Fig. 3 is a section of a rear corner of the

shell, showing a modified form of ring, and Fig. 4 is a similar view of still another form of ring.

In the drawings the numeral 10 indicates 5 a shell body provided with an explosive containing cavity 11 closed by a base plug 12 screw-threadedly engaging the body of the shell. The base plug is provided with the usual flange 13. A fuse seat 14 and a 10 fuse plug seat 15 are shown, these being of the usual construction. The base 16 is preferably counterbored as at 17 to a diameter in excess of the diameter of the base plug flange, for a purpose to be more fully 15 hereinafter set forth.

A rotating band 18 of usual construction is provided seated in a bandscore 19, the rear edge of the bandscore is indicated by the numeral 20.

20 In order to weaken the rear edge of the shell and to provide a pre-determined point of fracture, I cut an annular inwardly directed groove 21, the bottom of which is indicated by the numeral 22. In forming 25 the annular groove 21 the inner wall thereof is shouldered as indicated at 23. The bottom 22 of this annular groove is in close proximity to the rear edge 20 of the bandscore whereby the shell body is weakened 30 circumferentially on the line 24, thereby providing the desired predetermined point of fracture.

In order to close the opening caused by the groove 21 and to form in the base 16 an 35 annular cavity I provide a filler ring 25, preferably of soft steel. This ring is provided with an inclined face 26 adapted to abut a similarly inclined face formed on the base plug flange 13. For uniting the filler 40 ring 25 with the base plug flange 13, I provide a multiplicity of radially disposed screw-threaded pins 27 which project radially through the ring 25 and are screw-threaded into the base plug flange 13. By 45 inclining the contacting face of the filler ring and the base plug flange as indicated a radial pressure on the base of the shell which is sufficient to cause a fracture to the rear edge thereof will simultaneously tend 50 to force the ring 25 outwardly free of the base of the projectile, thereby shearing off the pins 27 and providing the desired clearance for the edge of the shell about to be broken off.

55 In Fig. 3 a slightly modified form of filler ring has been illustrated. In this form instead of providing a separate filler ring 25 the base plug flange 13 is made of greater diameter and provided with an inclined face 50 28. In this instance the base 16 has been counterbored, the wall thereof being inclined so as to properly receive the base plug flange with its inclined face 28. In this form the extended flange of the base

65 plug flange is provided with an annular groove 29. When radial pressure is exerted upon the rear edge of the shell, sufficient to cause a fracture, the portion of the flange beyond the circular groove 29 will be broken off by reason of the same being weakened. 70 This will provide the necessary clearance for the edge of the shell to insure its complete fracture.

In Fig. 4 still another modification of the 75 filler ring is illustrated. In this instance no positive connection is made between the filler ring 25 and the base plug flange 13. The filler ring is however, provided with an inwardly extending lip 30 and the base plug flange is correspondingly recessed. The filler 80 ring 25 is inserted in the counterbore 17 and the base plug is thereafter screwed into position. By reason of the lip 30 the base plug flange 13 will prevent axial displacement of the filler ring 25. Upon fracture 85 of the rear edge of the shell, however, the filler ring will be displaced because the pressure against the rear end of the shell which tends to displace the filler ring 25 will break off the annular lip 30. 90

When the projectile of the form as described strikes the armor plate of a vessel at an angle from normal, the point of the shell will in a usual manner punch a hole so that the shell can enter the armor. As the body of the projectile attempts to pass through the opening thus formed the angle formed by the armor plate and the axis of the projectile will have changed, the projectile tending first to swing out so as to 100 enter at approximately 90° with respect to the armor plate and subsequently whipping around so that its longitudinal axis forms with the armor plate an obtuse angle where previously there had been an acute angle. 105 This whipping or swinging motion of the rear edge of the shell causes its side to contact with the opening in the armor plate, the force being exerted in a radial direction upon the base of the shell. Instead of fracturing the shell body the radial pressure causes the rear edge of the shell to break along the line 24 or along the pre-determined point of fracture. This line of weakness is sufficiently to the rear of the bursting charge 115 cavity so that the fracture of the shell will not disturb the bursting charge as would be the case with shells of the usual construction.

As hereinbefore stated, the pressure exerted 120 upon the rear edge of the shell will tend to displace the filler ring 25 by sliding the same rearwardly and axially with respect to the shell, by reason of the inclined face 26, thereby shearing off the pins 27. 125

In the two modified forms of filler rings illustrated the construction is such that upon fracture of the rear edge of the shell the

ring will be discarded in order to provide a clearance necessary for a positive fracture of this rear edge of the shell.

Also it should be noted that the pressure which causes a fracture to the rear edge of the shell, will not be exerted directly upon that portion of the shell body which immediately surrounds the base plug. The annular weakening groove 21 so separates the outer portion of the base of the projectile from the inner portion which immediately surrounds the base plug, that the pressure exerted on the outer portion will in most instances break the same off from the projectile before causing a pressure upon the inner portion of the shell which is sufficient to disturb the base plug.

The prime feature of my invention resides in the provision of a weakening groove so disposed in the base of the projectile as to lie adjacent the rear edge of the bandscore. It is obvious that various means such as filler rings or extensions of the base plug flange may be employed for closing the mouth of this annular weakening groove. The essential feature of this filling means in each instance being that it be capable of being discarded quickly when the fracture of the rear edge of the shell occurs.

In constructing the annular groove 21 a tool of greater width is used to cut the groove down to the shoulder 23 and thereafter a tool of smaller guage is used to cut the groove to its bottom 22. It is obvious that if desired a groove of the same thickness from its mouth to its base may be formed.

Having thus described my invention, what I claim is:

1. An armor piercing projectile characterized by a line of weakness from the bandscore to the base, said line of weakness formed by an upwardly directed groove in the shell base, thereby weakening the shell body on a line from the inner rear edge of the band score to the inner end of the groove. 40

2. An armor piercing projectile characterized by the provision of an annular groove in the shell base, said groove cooperating with the rear edge of the bandscore, the distance between said annular groove 50 and the inner rear edge of said bandscore being less than the minimum distance from the surface of the shell to the wall of the explosive chamber, and also less than the distance from the groove to the periphery of 55 the shell base.

3. An armor piercing projectile characterized by the provision of a weakening groove in the base of the shell body and a filler ring covering the open mouth of said 60 groove, said ring being formed integrally with the flange of the base plug of the projectile and being provided with an annular weakening groove, the edge of said integral ring being inclined. 65

4. An armor piercing projectile having a flanged base plug characterized by a line of weakness from the bandscore to the base, said line of weakness being formed by an upwardly directed groove in the shell base, 70 thereby weakening the shell body on a line from the inner rear edge of the band score to the inner end of the groove and a filler ring secured to the flange of said base plug and covering the mouth of said groove.

WILLIAM J. TUCKER.
